CLAIM

The ornamental design for a fishing reel cover, as shown and described.

DESCRIPTION

FIG. 1 is a back perspective view of the fishing reel cover in accordance with our new design;

FIG. 2 is a front perspective view of the fishing reel cover in accordance with our new design;

FIG. 3 is a bottom plan view of the fishing reel cover in accordance with our new design;

FIG. 4 is a top plan view of the fishing reel cover in accordance with our new design;

FIG. 5 is a first side elevation view of the fishing reel cover in accordance with our new design;

FIG. 6 is a second side elevation view of the fishing reel cover in accordance with our new design;

FIG. 7 is a back plan view of the fishing reel cover in accordance with our new design; and,

FIG. 8 is a front plan view of the fishing reel cover in accordance with our new design.

The broken line showing environment (the remaining structure of the fishing reel cover) in the Figures is for illustrative purposes only and form no part of the claimed design.

1 Claim, 6 Drawing Sheets
